UNITED STATES PATENT OFFICE

HARRY B. HULL, OF DAYTON, OHIO, ASSIGNOR TO FRIGIDAIRE CORPORATION, OF DAYTON, OHIO, A CORPORATION OF DELAWARE

REFRIGERATING APPARATUS

Application filed October 31, 1928. Serial No. 318,254.

This invention relates to refrigerating apparatus particularly to compressors and driving means therefor.

One of the objects of the invention is to provide an improved means for reducing the noise incident to the operation of apparatus of this type.

More specifically it is an object of the invention to enclose the noisy parts of a refrigerating apparatus in a sound absorbing housing and to provide an improved means for dissipating the heat generated within the housing.

Another object of the invention is to provide sound absorbing means of a character indicated which is readily removable from the refrigerating apparatus to permit inspection and adjustment.

Another object of the invention is to provide a sound absorbing housing for enclosing the noisy parts of a refrigerating apparatus and exposing to the atmosphere heat generating parts which do not make noise.

Still another object is to provide an improved arrangement for cooling such exposed parts.

More specifically it is one of the objects of the invention to provide means actuated by the power plant within the housing for cooling the parts outside of the housing.

Another object is to transmit power through the wall of the housing to cool parts outside of the housing without direct mechanical connection between the prime mover and the driven element.

Further objects and advantages of the present invention will be apparent from the following description, reference being had to the accompanying drawings, wherein a preferred form of the present invention is clearly shown.

In the drawings:

Fig. 1 is a horizontal section of a refrigerating apparatus constructed in accordance with the invention;

Fig. 2 is a vertical section of the apparatus shown in Fig. 1;

Fig. 3 is a section corresponding to Fig. 1 of a modified form of the apparatus, this figure being taken on the line 3-3 of Fig. 4;

Fig. 4 is a section of the line 4-4 of Fig. 3; and Fig. 5 is a diagrammatic view of still another form of the construction.

Referring to the drawings 10 designates any suitable base upon which is mounted a compressor 11 and a motor 12 which drives the compressor through a belt 13 and pulley wheels 14 and 15. Connected to the compressor is a condenser 18 which receives compressed gaseous refrigerant from the compressor, cools and liquefies the refrigerant and discharges the refrigerant to a receiver or reservoir 19. If desired, for the sake of convenience, the receiver may be mounted on a pair of brackets 20 supported in the base 10. The brackets 20 also support a housing 22 containing a switch for controlling the motor. Since it is the motor, compressor and switch of the moving parts which make noise in operation, I propose to prevent annoyance by preventing such noise from transmitting to occupied rooms. This may be accomplished by completely enclosing the noisy parts of the apparatus in a housing which prevents the transmission of sound from the apparatus to distant points. As shown in the drawings this housing may include a base 25 upon which the apparatus is supported, and a housing proper consisting of side walls 26 and a cover 27. The base and housing may be made of any suitable material, preferably some material which absorbs sound waves and prevents the transmission of sound through the housing.

Since the motor, compressor and condenser all generate heat during operation and since this heat must be removed, I provide means for dissipating to the outside atmosphere heat generated. Since the condenser does not make noise this may be placed outside of the housing where it is cooled by contact with the atmosphere which cooling may be enhanced by circulating air over the condenser in any desired manner.

Since the motor, compressor and switch may need periodic inspection and adjustment the walls 26 and cover 27 are preferably formed as one structure which is removably supported on the base 25. The housing may be held in place on the base in any suitable

manner. I prefer to hermetically seal the interior of the housing in order to prevent transmission of sound therefrom. Therefore the joint at the housing and base 25 is sealed in any suitable manner, as for example, by flexible sealing means such as a grooved strip 35 of soft rubber which fits tightly in a groove in the base 25 and the grooved part of the strip is adapted to snugly embrace the bottom of the housing. Suitable openings 39 are provided in the rubber strip through which the pipes may extend and the strip may be slit upwardly from these openings, if desired, so as to permit the removal of the pipes. One of the walls 26' 15 is formed with a re-entrant portion 28 which provides a discharge chamber 29 and an inlet chamber 30. The discharge chamber 29 is separated from the rest of the housing by means of a partition 31 provided with an opening to receive the fan. Tubes 33 provided with fins 34 lead from the discharge to the inlet outside of the housing and provide heat exchange means associated with the outside atmosphere for dissipating the heat generated within the housing. The fan circulates air through the housing into the discharge chamber 29, into the passage along the tubes 33 and is cooled therein and enters 25 the chamber 30 as cooled air which again passes over the apparatus and absorbs heat therefrom.

If desired, for example, in an apparatus of a large capacity additional means may be 35 provided for cooling the condenser outside of the housing. As shown in Fig. 5 fan 40 driven by motor 41 is mounted adjacent the condenser. The motor 41 being connected in parallel with the motor 12 and controlled by 40 the same switch, consequently, whenever the motor 12 is running, that is, when the compressor is being operated to cool the condenser it may be advantageous to mount the condenser adjacent the tubes 33 in order that 45 the air from the fan 40 may assist in circulating air over the tubes. Still another arrangement for cooling the condenser outside the housing is shown in Figs. 3 and 4. In this arrangement a bearing 43 is supported 50 in one of the walls 26 and carries a power shaft 44 extending through the wall into the discharge chamber 29. A wind wheel 45 is mounted on the inside of the shaft adjacent the fan 31a and in the path of the air stream 55 whenever the fan 31a is operating and thus imparts power to a fan 46 on the outer end of the shaft adjacent the condenser. This arrangement provides a simple and economical means for transmitting power from the motor 60 within the housing to a motor for driving the condenser fan and obviously does not interfere with the removability of the housing.

While the form of embodiment of the invention as herein disclosed constitutes a preferred form, it is to be understood that other

forms might be adopted, all coming within the scope of the claims which follow.

What is claimed is as follows:

1. Refrigerating apparatus comprising in combination a compressor, means for driving the compressor, a housing completely inclosing the compressor and driving means, said housing including at least one passage in heat exchange relation with the outside atmosphere and means for circulating the air confined in the housing through said passage and over the compressor and driving means. 75

2. Refrigerating apparatus comprising in combination a compressor, means for driving the compressor, a housing completely inclosing the compressor and driving means, said housing including at least one passage in heat exchange relation with the outside atmosphere, and means actuated by the driving means for circulating the air confined in the 80 housing through said passage and over the compressor and driving means. 85

3. Refrigerating apparatus comprising in combination a compressor, means for driving the compressor, a housing completely inclosing the compressor and driving means, a tube connected at both ends with the housing and disposed outside said housing and means for circulating the air confined in the housing 90 through said tube and over the compressor 95 and driving means.

4. Refrigerating apparatus comprising in combination a compressor, means for driving the compressor, a housing completely inclosing the compressor and driving means, said 100 housing including a re-entrant wall providing inlet and discharge chambers within said housing, a tube connecting the chambers outside of the housing, and means for impelling the air confined in the housing into 105 the discharge chamber.

5. Refrigerating apparatus comprising in combination a compressor, means for driving the compressor, a housing completely inclosing the compressor and driving means, a condenser outside the housing connected to the compressor, a power transmitting member extending through a wall of the housing, a fan actuated by said driving means for circulating the air confined within the housing, a 110 wind wheel on the power transmitting member disposed in the air stream of the fan, and a second fan on the power transmitting member outside the housing for circulating air 115 over the condenser. 120

6. Apparatus as defined in claim 5 in which the power transmitting member is a shaft supported by the housing.

7. Apparatus as defined in claim 5 in which the housing includes a re-entrant wall providing discharge and inlet chambers and said wind wheel is located within said discharge chamber. 125

8. Refrigerating apparatus comprising in combination a compressor, means for driving 130

the compressor, a housing completely enclosing the compressor and driving means, a condenser outside of said housing and connected to said compressor, means actuated by said driving means for circulating air within said housing and means actuated by the circulating air within the housing for circulating air over said condenser.

5 In testimony whereof I hereto affix my signature.
